ADRIAN L. H. VERWYS AND VINCENT VERWYS, OF GRAND RAPIDS, MICHIGAN.

GEARING FOR LATHES.

Application filed May 17, 1927. Serial No. 191,984.

This invention relates to an improvement in wood turning lathes and is more particularly concerned in improvements in the mechanism shown in the issued patent to 5 James Hoogerhyde, No. 1,546,447, issued July 21, 1925.

In the patent to Hoogerhyde the part of the machine which holds the work to be turned is moved back and forth, toward and 10 away from the cutters which act upon the work. It is desirable at times that such work shall not have any rotative movement, this being effected by disconnecting certain driving gearing. It is also, by reason of 15 the swinging mount of the part of the machine which carries the work, necessary for the practical operation of the machine to provide proper mountings of the parts to permit movements for effecting such gear- 20 ing connections and disconnections without binding or cramping, and it is primarily to these ends that the present invention is directed, to produce a practical and operative construction which eliminates all cramping 25 and binding between the parts so that the necessary movements for effecting connection or disconnection of the gearing which controls the rotating movement of the work may be made.

30 The construction for the attainment of these ends, as well as many others not specifically stated at this time, will be apparent from the following description taken in connection with the accompanying drawing, in 35 which,

Fig. 1 is an end elevation of the wood turning lathe, certain parts being removed and shown in section.

Fig. 2 is an enlarged elevation of the gearing used for controlling the rotation of the work, the gearing being shown connected in 40 Fig. 2, while in Fig. 1 it is shown disconnected, and

Fig. 3 is a fragmentary enlarged front 45 elevation, with parts in section to better illustrate the construction, the plane of section being substantially on line 3-3 of Fig. 1.

Like reference characters refer to like 50 parts in the different figures of the drawing.

The pedestal or main support for the machine is indicated at 1 and at its upper end it carries a rotating series of cutters (not 55 shown) which are driven by a motor 2.

Bracket arms 3 are attached to the front of the main support 1 extending substantially horizontal therefrom. A rock shaft 4 is rotatably mounted between and carried by the arms 3 to which a handle 5 is attached for the purpose of manually rocking the shaft. An arm 6 is connected to the shaft 4 and one end thereof is connected by link 7 to the tilting frame 8 which supports the work holding devices. 60

Frame 8 is pivotally mounted at its lower end on a shaft 9 which in turn is carried in suitable bearings extending forward from the support 1 as shown in Fig. 3. Accordingly, the frame 8 is tiltable about the axis of the shaft 9 toward or away from the cutters of the machine. 65

At the upper end and to one side of the frame 8 a housing 10 is permanently secured into which a shaft 11 extends on which a worm wheel 12 is secured. The rotation of the wheel 12 controls the rotation of the head stock spindle carried by frame 8, with which the work is connected in the operation of the machine. 70

A horizontal partition 13 extends from the front side of the housing 10 forward a distance being located above the bottom of the housing and at its upper side and near its end having a concave bearing surface, 75 as best shown in Fig. 2, while the upper end of the housing is similarly concaved but in the opposite direction, as indicated at 14. A stirrup member having two ends or heads 15 and 16 connected at one side by a vertical section 17 is mounted between the upper end 14 of the housing and the partition 13, the upper and lower sides of the two heads 15 and 16 being of convex shape so as to fit the concave bearing surfaces at 80 14 and on the partition 13. 90

A shaft 18 lies along the end of the tilting frame 8 and at its upper end passes into the housing 10 and through openings in the partition 13 and head 16, said openings being elongated and longer than the diameter of the shaft. A worm 19 is secured to the upper end portion of the shaft 18. The upper end of the shaft is rotatably mounted in a bearing 20 which is directly 100 below the head 15 while the shaft below said worm passes another bearing 20 located against the upper side of the part 16. The two bearings 20 are connected by vertical bar 20^a and the same are held in position 105

110

by plates 15^a and 16^a secured to the free edges of the heads 15 and 16 previously described. In this way the two bearings 20 with their connecting member 20^a may have 5 a limited sliding movement so as to connect the work 19 to the work wheel 12 or disconnect it therefrom. As will later be described the worm 19 normally is in engagement with the wheel 12.

10 Shaft 18 at its lower end extends through a housing 21 fixed to the lower end of the frame 8 as shown in Fig. 3. Within said housing the shaft is equipped with two bevelled gears 22 spaced apart and idle on the 15 shaft both being in mesh with a bevelled gear 23 fixed on the end of a drive shaft 24 located in direct alignment with the shaft 9. A suitable reversing clutch 25 for the purpose of connecting either gear 22 with 20 the shaft 18 is mounted on said shaft 18 between the gears 22.

To the connecting bar 20^a between the bearings 20^a a rod is secured which extends forward through the front side of the housing 10 and is equipped with a knob 26 for manual operation. A spring 26^a is located around the rod as shown in Figs. 1 and 2 and its normal effect is to move the worm 19 into engagement with the work wheel 12. However, by grasping the knob and pulling outwardly on the same the spring may be compressed and worm and wheel 12 freed from engagement with each other. The knob is equipped with the usual finger 35 which, when the knob is pulled out and turned engages against the outer side of the housing so as to hold the parts disengaged. There is also associated with the machine the lever 27 pivotally mounted between its ends on one end of the tilting frame 8, one end of the lever extending upwardly into the housing and engaging with the vertical connecting bar 20^a while the other end is equipped with a roller to ride 40 on a cam 28 fixed to one end of the main support or pedestal 1.

When the tilting frame 8 with the mechanism mounted thereon is moved forward to the position shown in Fig. 1 and the work 50 is moved away from the cutters, there occurs an automatic disconnection of the worm 19 from the worm wheel 12; and when it is tilted in the opposite direction to bring the work in conjunction with the cutters, 55 before which conjunction of cutters and work occurs the worm and worm wheel are brought into connection by the spring 26^a which is free to act when the lower end of lever 27 passes in front of the cam 28. It 60 is also evident that by use of the knob 26 such disconnection of the worm and worm wheel may be made at any time irrespective of the position of the work with respect to the cutters. This may be desirable at 65 times.

In any case whenever, the worm 19 and the worm wheel 12 are connected or disconnected, the shaft 18 turns about the axis of the shafts 9 and 24 and the bearing made by the heads 15 and 16 connected between 70 member 17 has a self aligning rotative movement about a center midway between the two heads 15 and 16. This obviates any tendency of the parts to cramp or bind which otherwise would occur. This is a 75 primary feature of importance in the present invention, namely, the prevention of this cramping and binding action when the shaft 18 at its upper end moves with respect to the housing 10 and with respect to the worm wheel 12 in the engagement of the worm 19 with the wheel 12 or in its disengagement therefrom.

There are many variations in the specific 80 details of structure which may be resorted to to secure this result. While the structure shown and described is practical and operative and is used in production the invention is not to be limited specifically thereto but is to be considered comprehensive of 85 all forms of structure for attaining the same result by equivalent means comprehended by the claims appended hereto defining the invention.

We claim:

1. In a machine of the class described, a main support, a tilting frame mounted on the main support to move toward or away therefrom, a driven shaft paralleling one end of the main support and tiltable therewith, a gear adapted to be driven by said shaft, gearing on said shaft to engage with said gear, means normally tending to hold said gearing and gear in engagement, means for automatically separating said gearing and gear on outward tilting movement of the tilting frame, bearings for the upper end of said shaft, a self aligning movable support for said bearings through the lower end of which the shaft passes having convexed upper and lower ends and bearing members having concave surfaces with which said convexed surfaces engage, substantially as and for the purposes described. 100

2. In a machine of the class described, a main support, a tilting frame mounted at the front of said main support for movement about a horizontal axis toward or away from the main support, a driven shaft paralleling one end of the tilting frame and movable with said frame, a housing carried by the tilting frame into which the upper end portion of said shaft is received, a second shaft extending into said housing, a worm wheel on said second shaft, a worm 105 on the first shaft to engage with said worm wheel, bearings for the upper end of the first shaft, a member carrying said bearings having curved upper and lower ends, the upper ends of said member engaging against 110

- the upper end of said housing, said upper end of the housing being curved to conform to the upper end of said member, and a partition carried in said housing having a concaved upper side against which the lower end of said bearing carrying member engages, whereby the first shaft may move freely to engage the worm thereon with the worm wheel or disengage it therefrom.
- 10 3. In a machine of the class described, a main support, a substantially vertical frame mounted at its lower end on said main support to tilt about a horizontal axis and move toward or away from said main support, a shaft located alongside one end of said tilting frame and movable with said frame, a housing at the upper end of the tilting frame into which the shaft passes, a second shaft extending into said housing, a worm wheel 20 on said second shaft, a worm on said first shaft adapted to engage with said wheel, a movable bearing at the upper end of the first shaft whereby it may be moved so as to engage the worm with or disengage it from the worm wheel, and a self aligning member mounted within the housing and movable to different positions about a relatively fixed center on which member said movable bearing is supported whereby the first shaft
- may be freely moved with respect to the second shaft and the worm wheel carried thereby.
4. In a machine of the class described, a main support, a frame located in front of the main support and tiltably mounted at its lower end on said support to turn about a horizontal axis toward or away from the support, a shaft mounted along one end of the tilting frame and movable therewith, a second shaft mounted horizontally at the upper end of the tilting frame, interengaging gearing on said shaft for driving the second shaft from the first shaft when said gearing is in engagement, said first shaft being movable about the tilting axis of the tilting frame to disengage said gearing, and a support for the upper end of said first shaft carrying bearings for the shaft, said support being shiftable about a relatively fixed center and having ends formed as arcs of circles about said center, and means bearing against each end of the said support having curved surfaces to conform to the curved surfaces on the ends of said support.

In testimony whereof we affix our signatures.
